UNITED STATES PATENT OFFICE.

CHARLES C. MCCLINTOCK, OF LOS ANGELES, CALIFORNIA.

FOMENTATION-TANK.

1,314,681.

Specification of Letters Patent. Patented Sept. 2, 1919.

Application filed May 3, 1919. Serial No. 294,470.

To all whom it may concern:

Be it known that I, CHARLES C. MCCLINTOCK, a citizen of the United States, residing at Los Angeles, in the county of Los Angeles and State of California, have invented certain new and useful Improvements in Fomentation-Tanks, of which the following is a specification, reference being had to the accompanying drawings.

10 This invention relates to certain improvements in fomentation tanks, and it is an object of the invention to provide a novel and improved device of this general character of a portable type and which is particularly adapted for use in the steaming or heating of cloths for use in connection with the treatment of various diseases.

It is also an object of the invention to provide a novel and improved device of this 20 general character including a steam chamber, together with electrical heating means for vaporizing the liquid.

A further object of the invention is to provide a novel and improved device of this 25 general character consisting of two separable sections, one of said sections being provided with a heating means and a second section constituting a steam chamber, together with a reservoir carried by the second section and wherein the delivery of fluid from the reservoir to the action of the heating means is automatically controlled.

Another object of the invention is to provide a novel and improved device of this 35 general character including a steam chamber and wherein said steam chamber is provided with means to support a cloth therein so that the cloth may be effectively steamed or heated.

40 The invention consists in the details of construction and in the combination and arrangement of the several parts of my improved fomentation tank whereby certain important advantages are attained and the 45 device rendered simpler, less expensive and otherwise more convenient and advantageous for use, as will be hereinafter more fully set forth.

The novel features of my invention will 50 hereinafter be definitely claimed.

In order that my invention may be the better understood, I will now proceed to describe the same with reference to the accompanying drawings, wherein:

55 Figure 1 is a vertical longitudinal sec-

tional view taken through a fomentation tank constructed in accordance with an embodiment of my invention.

Fig. 2 is a sectional view taken substantially on the line 2—2 of Fig. 1. 60

Fig. 3 is a transverse vertical sectional view taken through the upper or top section of the device as herein disclosed.

Fig. 4 is a view similar to Fig. 3 but showing certain of the parts in a second 65 position.

Fig. 5 is an enlarged sectional view taken substantially on the line 5—5 of Fig. 1, and

Fig. 6 is a fragmentary view partly in section and partly in elevation illustrating 70 a locking means for controlling the opening or closing movements of the doors for the heating chambers or compartments of the upper or top section of the device.

As herein disclosed, my improved fomentation tank comprises two separable sections A and B. The lower section A has its upper or top face open and arranged within said lower or base section A is a heating means H having positioned therebeneath 75 and in close proximity thereto a reflector a or the like which serves to materially facilitate the action of the heating unit. In practice, it is preferred that the heating means H comprise a plurality of electric heating 80 coils of a conventional type with each coil controlled by an individual switch or rheostat, but as the particular construction and arrangement thereof forms no part of my present invention it is not believed that a 90 detail description and illustration thereof are necessary.

The upper or top section B comprises a closed chamber divided into two compartments C by the transversely disposed partition 1 having its lower end terminating above the bottom of the upper or top section B but adapted to extend below the normal water level within said section when the device is in operation, so that the water or 100 other fluid serves to seal the communication between the compartments C.

The bottom of the upper or top section B is defined by the depending flanges 2 extending within the bottom or base section 105 A and an end flange 2 is engaged with an inwardly directed lug 3 carried by the adjacent end wall of the bottom or base section A. The opposite end flange 2 rests upon an inwardly directed flange 4 carried 110

by the adjacent end wall of the base or bottom section A and coacting with this end flange 2 is a pivoted holding member 5 of any preferred construction. By this arrangement, the sections A and B may be maintained in assembled relation but readily separated when the requirements of practice may so necessitate. In order that the device may be readily transported, I find it of advantage to provide the top wall of the upper section B with a handle or hand grasp G.

10 The sides and top of the upper or top section B are provided with communicating reservoirs R and the lower portions of the side reservoirs are connected by the pipe 6, and said reservoirs are filled through the vent 7 in the top of the section B and which vent is normally closed by the plug 8.

15 One of the side reservoirs adjacent its lower end has in communication therewith a discharge vent 9 including an upstanding portion with which coacts the controlling or check valve 10. The valve 10 is carried by 20 an end portion of an arm 11 pivotally supported intermediate its length for rocking movement in a vertical path. Suitably secured to the outer end portion of the arm 11 is the float F so that the valve 10 will be 25 opened and closed as the water level within the upper or top member B rises or falls, whereby substantially a constant water level is maintained within the section B.

30 Disposed through the float F is a stem 12 which extends above and below said float and the lower end portion of the stem is operatively connected with a switch S interposed in the main line leading to the heating medium H from a source of electrical energy 35 so that should the water level in the section B become unduly low, the switch S will be opened to cut out the heating member H and thereby prevent damage to the device and eliminate the possibility of fire.

40 45 14 denotes a spring arm constantly bearing down upon the upper end of the stem 12 in order to assure a proper cut out of the heating member H when the water level within the section B becomes too low. It 50 will be understood that when the normal water level within the section B is restored, the rising of the float F will result in the closing of the switch S.

55 A side face of the upper or top section B has in communication with each of the compartments C an opening 15 preferably rectangular in form and coacting with each of said openings 15 is a pair of doors D and D'. The outer door D is hingedly connected at 60 its lower end with the adjacent face of the section B at a point below the opening 15 and the marginal portions of said door are provided with the inwardly directed flanges 16 which, when the door D is closed, snugly 65 fits between the side members of the inwardly

directed and outwardly opening flange 17 defining the opening 15. By this arrangement, with low steam pressure within the coacting chamber C, said chamber is rendered substantially steam-tight when the 70 door D is in closed position.

When the door D is closed, the coacting door D' is positioned adjacent the opposite side wall of the door D, as clearly indicated in Figs. 1 and 2. Engaged with the door 75 D' are the links 18 in vertical spaced relation and converging toward the door D with the upper link 18 substantially horizontally disposed. The converging end portions of the links 18 are slidably engaged with the 80 door D so that when the door D is swung into open position, the door D' will be pulled forwardly and caused to close the opening 15.

85 The marginal portion of the door D' is defined by the forwardly extending flanges 19 which engage over the flanges 17 when the door D' is in closed position and in order to effect a substantially steam-tight joint. The door D' rests upon and travels along the tracks 20 arranged within each of the compartments C and disposed transversely of the section B, whereby the desired closing 90 action of the door D', when the door D is opened, is assured.

95 Each of the doors D is provided adjacent its top with an inwardly directed rack 21 while the upper portion of each of the doors D' is provided with a forwardly directed rack 22. Woolen cloths or the like are 100 adapted to be suspended from the racks 21 and 22 and when the door D is closed, the cloths thus suspended will be thoroughly steamed or heated while within a compartment C.

105 In practice, it is preferred that when one of the doors D is in open position, the second door D' be held in closed position, and in the present embodiment of my invention, this is accomplished by the rock arm 23 supported substantially midway its length for 110 swinging movement in a vertical path by the partition 1. Said arm 23 extends through the partition 1 into each of the compartments C above the horizontally disposed links 18. Each of the links 18 in its upper edge and adjacent its outer or forward end is provided with a notch or recess 24 having leading thereto from the rear a cam edge 25. When the doors D are in closed position, the arm 23 is free of the notches or recesses 24, but when one of the doors D is moved outwardly into open position, the cam edge 25 will engage one portion of the arm 23 and force said end portion upwardly resulting in the opposite end portion of the arm 23 being swung downwardly into the notch or recess 24 in the upper link 18 coacting with the second door D', so that when one of the doors D is opened, the second door D is locked against outward movement. By 120 125 130

this means, an effective steaming or heating of the cloths within one compartment C may be effected while cloths are being removed from or applied within a second compartment.

It is also desired that when the water level within the upper or top section B is too low the doors D be held against movement and, as herein disclosed, the lower flange of each of the doors D' is provided with a depend-

ing lug 26 with which engages a rock arm 27 carried by a shaft 28 rotatably supported within the section B below the tracks 20 and extending longitudinally of the section B.

15 It is to be understood that there is a rock arm 27 for coaction with each of the lugs 26.

An end portion of the shaft 28 is provided with a depending rock arm 29 which extends below the float F so that when the float F falls, the contact of the float with the arm 29 will rotate the shaft 28 to cause the rock arms 27 to extend upwardly and one of said arms 27 will engage behind a lug 26 depending from a door D' in closed position, so that the return of said door D' into open position and the moving of the coacting door D will be prevented until the water level within the section B has been returned to normal.

30 Each of the doors D has engaged with the upper portion thereof a ring 30 or the like which affords means whereby the requisite manipulation of the door D may be conveniently accomplished.

35 From the foregoing description, it is thought to be obvious that a fomentation tank constructed in accordance with my invention is particularly well adapted for use by reason of the convenience and facility with which it may be assembled and operated, and it will also be obvious that my invention is susceptible of some change and modification without departing from the principles and spirit thereof and for this 40 reason I do not wish to be understood as limiting myself to the precise arrangement and formation of the several parts herein shown in carrying out my invention in practice except as hereinafter claimed.

45 50 I claim:

1. A device of the class described comprising a steam chamber divided into a plurality of compartments, each of said compartments having an opening in communication therewith, a door coacting with each of the openings, and means operated by a door when the same is moved into open position for locking the remainder of the doors in closed position.

55 60 65 2. A device of the class described comprising a steam chamber, a reservoir, a float for controlling the delivery from the reservoir within the chamber, said chamber having an opening in communication therewith, a door coacting with said opening, and

means under control of the float for locking the door in closed position upon lowering of the float.

3. A device of the class described comprising a steam chamber, a reservoir, a float 70 for controlling the delivery from the reservoir within the chamber, a heating means coacting with the chamber, and means operable by the float for controlling the heating means.

4. A device of the character described comprising a steam chamber, said chamber having an opening in communication therewith, a door coacting with said opening, and means under buoyant control for locking the door in closed position.

5. A device of the class described comprising a chamber, a reservoir delivering within the chamber, a float for controlling the delivery from the reservoir to the chamber, said chamber having an opening in communication therewith, a door coacting with said opening, a rock shaft extending within the reservoir and the chamber, a rock arm carried by the shaft, said shaft being provided with means whereby the same is rotated upon lowering of the float to move the rock arm from a position for locking the door against movement.

6. A device of the class described including a chamber having an opening, a pair of doors coacting with said opening, one of said doors having swinging movement, and a link connecting said doors, said link having sliding connection with one of the doors 100 and pivotal connection with the second door.

7. A device of the class described including a chamber having an opening, a pair of doors coacting with said opening, one of said doors having swinging movement, and 105 a link connecting said doors, said link having sliding connection with one of the doors and pivotal connection with the second door, said second door having substantially rectilinear movement.

8. A device of the class described including a chamber having an opening, a pair of doors coacting with said opening, one of said doors having swinging movement, a link connecting said doors, said link having 115 sliding connection with one of the doors and pivotal connection with the second door, and means engageable with the link for holding the doors against movement.

9. A device of the character described including a chamber divided into a plurality of compartments, each of said compartments having an opening in communication therewith, a door coacting with each of the compartments, and a member common to all of 120 the compartments operating upon movement of a door into open position to lock the remainders of the doors in closed position.

10. A device of the class described comprising a chamber divided into two com- 130

partments, each of said compartments having an opening in communication therewith, a door coacting with each of the openings, a movable arm extending within each of the compartments and operating upon movement of one of the doors into open position to lock the second door in closed position.

11. A device of the character described including a chamber having an opening, said opening being defined by an inwardly directed flange substantially U-shaped in form and opening outwardly, and a pair of connected doors coacting with the opening, one of said doors being provided with an in-

wardly directed flange fitting within the first named flange when said door is in closed position, the second door being provided with a flange overlying said first named flange when the second door is in closed position, one of said doors being in a closed position when the other door is in open position.

In testimony whereof I hereunto affix my signature in the presence of two witnesses.

CHARLES C. McCLINTOCK.
